United States Patent Office

Des. 202,413

Patented Sept. 28, 1965

202,413

URINAL

James A. Tiller, Louisville, Ky., assignor to American Radiator & Standard Sanitary Corporation, New York, N.Y., a corporation of Delaware

Original application Apr. 9, 1962, Ser. No. 69,624, now Design Patent No. 201,272. Divided and this application Dec. 24, 1964, Ser. No. 83,650

Term of patent 14 years

(Cl. D4—5)

Fig. 1.

Fig. 2.

Fig. 3.

FIG. 1 is a front perspective view of my new design for a urinal.

FIG. 2 is an elevational side view of my new design for a urinal.

FIG. 3 is an elevational rear view of my new design for a urinal.

This is a division of application Serial No. D69,624 filed April 9, 1962, now U.S. Patent No. 201,272.

The dominant features of my design reside in the portions shown in full lines.

I claim:

The new and ornamental design for a urinal, substantially as shown and described.
